UNITED STATES PATENT OFFICE.

CHARLES J. TÓTH, OF NEW YORK, N. Y., ASSIGNOR TO INTERNATIONAL PROCESS AND ENGINEERING CORPORATION, OF NEW YORK, N. Y., A CORPORATION OF NEW YORK.

INTERNAL-COMBUSTION ENGINE.

Application filed March 16, 1922. Serial No. 544,359.

To all whom it may concern:

Be it known that I, CHARLES J. TÓTH, a citizen of the Republic of Uruguay, and resident of 322 West 57th St., New York city, ⁵ county and State of New York, have invented certain new and useful Improvements in Internal-Combustion Engines, of which the following is a specification.

The invention relates to internal combustion engines, and particularly to such engines of the two cycle type. One of the objects of the invention is the provision of an improved engine of this type having its parts so constructed and related as to provide for "supercharging" the cylinder. In the present construction the exhaust ports of the cylinder are closed, cyclically, before the inlet ports are closed. The air or mixture thus continues to pass through the inlet ports into the cylinder during the interval between the closing of the exhaust ports and the closing of the inlet ports, and this continued charging of the cylinder after the exhaust ports have closed is what is referred ¹⁰ to herein as the "supercharging" of the cylinder. In the usual form of two-cycle engines such action is not possible, because of the fact that in them the exhaust ports remain open until after the inlet ports have closed, so that no air or mixture can be forced into the cylinder after the exhaust openings thereof have been closed, except by arrangements employing a valve as in a Diesel type of engine, which valve is eliminated in the present invention. ¹⁵

In attaining this supercharge a precompression chamber may be provided, in which chamber air or hydrocarbon fuel mixture, as the case may be, is compressed and then discharged into the combustion chamber through suitable ports.

In the embodiment of the invention herein shown and described, this supercharge is accomplished by providing two pistons operating in the cylinder, one being given a lead over the other, the first controlling the exhaust ports while the second controls the inlet ports; the arrangement and construction of the ports and the relative relation of the pistons being such that the exhaust

ports are closed before the inlet ports are closed, and such that the exhaust ports are opened before the inlet ports are opened.

In the preferred form of the invention as herein shown, a duplex cylinder is used having parallel cylinder portions in which operate pistons connected by connecting rods of equal length to the same throw of the crank shaft. The parallel cylinder portions are so arranged with respect to the crank shaft as to give one piston the desired lead over the other, and at the same time prevent either connecting rod from assuming such an angularity at any time as to impose excessive lateral stresses on the cylinder walls. ⁵⁵

Another object of the invention is the provision of improved precompression means, including in the preferred structure a precompression chamber beneath the pistons in the cylinder and above and separate from the crank case, the pistons being provided with portions which control the ports of this chamber. ⁷⁰

According to this invention, extremely effective scavenging may be had as well as the desired supercharging above mentioned. ⁷⁵

Other objects of the invention relate to the provision of improved features of construction and combinations of parts, as will be more fully set forth hereinafter. ⁸⁰

In order that a clearer understanding of the invention may be had attention is hereby directed to the accompanying drawings forming part of this application and illustrating one embodiment of the invention. In the drawings— ⁸⁵

Fig. 1 represents a vertical section taken through an engine embodying the invention; ⁹⁰

Figs. 2 and 3 are sections taken respectively on line 2—2 and line 3—3 of Fig. 1;

Fig. 4 is a vertical section taken on line 4—4 of Fig. 2; and

Fig. 5 is a diagram illustrating the operation of the engine. ⁹⁵

Referring to the drawings, an internal combustion engine is illustrated having a duplex cylinder which may comprise a casting 1 mounted above the crank case 2. The 100

cylinder is provided with two parallel downwardly extending cylinder portion 3 and 4 arranged side by side, with a common combustion chamber 5 above the same. The 5 crank shaft 6 is mounted in suitable bearings in the crank case and is provided with a single crank or throw 7. Pistons 8 and 9 are mounted for reciprocation in the two parallel cylinder portions 3 and 4 and are 10 connected by connecting rods 10 and 11 to crank 7, these rods being of equal length.

In Fig. 2 the intermediate portion 12 of the section line 4-4 lies in the vertical plane of the crank shaft. It will be noted 15 from this drawing that parallel cylinder portions 3 and 4 are arranged with their vertical axes located respectively on opposite sides of and at equal distances from the vertical plane of the center line of the 20 crank shaft, said portions being staggered and overlapping one with respect to the other along the direction of the crank shaft. Accordingly these portions 3 and 4 are symmetrical with respect to the center line of 25 the crank shaft, but overlap one another.

The cylinder portion 3 is provided with the exhaust ports 13, while the cylinder portion 4 is provided with the inlet ports 14. Cylinder portion 3 has an outer wall 3¹ spaced from the inner wall within which 30 piston 8 operates, and cylinder portion 4 has an outer wall 4¹ spaced from the inner wall in which piston 9 operates. Ports 13 and 14 extend through the inner walls of 35 the cylinders (Fig. 2), and an exhaust outlet 13¹ in the outer wall 3¹ opens into the annular space 13^a, from which ports 13 extend into cylinder portion 3.

The piston 9, (Fig. 1) is provided with 40 an inner hollow cylindrical portion 15¹, a top portion 16¹ and an outer concentric cylindrical portion 17¹. The piston 8 is similarly provided with portions 15, 16 and 17. This construction provides what I term a 45 differential piston, because of the fact that the piston provides one area, the upper surface of the entire piston, to serve as a working piston in the combustion chamber, while another, smaller area, an annular surface on 50 the under side of the piston, serves as a pre-compression piston, as will be explained hereinafter. A member 18, preferably a casting, is provided at the bottom of the two parallel cylinder portions 3 and 4, this 55 member having cylindrical guide portions 20, 20¹, which constitute guides for the inner cylindrical piston portions 15 and 15¹. Member 18 is also provided with horizontal flanges or diaphragm portions 21, which 60 serve to separate the interior of the crank case from a precompression chamber 27 provided above flanges 21, and hereafter to be described.

The engine may be adapted to operate on 65 a combustible mixture in which case the

combustion chamber 5 will be provided with the usual spark plugs, or air alone may be drawn into the engine through the inlet ports and compressed to a considerable degree in the combustion chamber, in which 70 case fuel will be injected into the combustion chamber through fuel injectors, at suitable times, as is the practice in the Diesel type of engine. I have illustrated the cylinder head 22 as provided with openings 23 75 in which spark plugs or fuel injectors may be positioned. The upper portion of the cylinder may be suitably water jacketed, as is indicated at 24. The division wall 25 between the two parallel cylinder portions in 80 which the pistons operate is illustrated in Fig. 4 as extending upwardly into the upper portion of the interior space of the cylinder.

Exhaust ports 13 are controlled by the 85 portion 17 of greatest diameter of piston 8 while the inlet ports 14 in the cylinder portion 4 are controlled by the portion 17¹ of greatest diameter of piston 9.

Ports 26 and 26¹, in cylinder portions 3 90 and 4 respectively, (see Fig. 3), serve as inlet ports for the precompression chamber 27, and are also controlled by the portions 17, 17¹, of greatest diameter of the pistons 8 and 9. The precompression chamber 27, 95 extends around cylinder portions 3 and 4, in the space above the horizontal flange 21 of member 18, within the outer walls 3¹ and 4¹, and around the annular upwardly extending flanges 20, 20¹, of member 18. An 100 intake opening 28 leads through the outer wall 4¹ of cylinder portion 4 into the annular space 28¹, which extends around cylinder portion 3, between the inner and outer walls thereof, and partly around cylinder 105 portion 4, between the inner and outer walls thereof, as shown in Fig. 3. The ports 26 and 26¹ are covered by the aprons or outer portions 17-17¹ of pistons 8 and 9 until, on the upstroke of the pistons, the outer portions 17-17¹ of the pistons begin to move 110 past these ports, when air or mixture will be free to occupy the unobstructed space above flanges 21, between the outer walls 3¹ and 4¹ and the inner cylindrical portions of 115 the pistons. That is to say, the precompression chamber will comprise the space between inner and outer walls 3 and 3¹, 4 and 4¹, the space below aprons 17, 17¹, and the bottoms of inner walls 3 and 4, and the 120 annular spaces between aprons 17, 17¹ and annular guides 20, 20¹, and between aprons 17, 17¹ and the inner cylindrical portions 125 of the pistons above guides 20, 20¹, when the pistons are raised above the positions shown in Figs. 1 and 4.

The inlet ports 26, as shown in Fig. 3, may be positioned at intervals throughout the circumference of the cylinder portion 3. The ports 26¹ in the cylinder portion 4, how- 130

ever, may be positioned throughout only a portion of the circumference of cylinder portion 4, so that room may be left for free communication between the precompression chamber 27 and the inlet ports 14 which lead from the precompression chamber into the upper portion of the cylinder. This communication is established when ports 14 are uncovered by the apron 17¹ of piston 9, by 10 way of the upwardly extending portion 27¹ of the chamber 27, which extends upwardly, at the right hand side of cylinder portion 4, to the level of ports 14, as is shown in Figs. 1 and 3.

15 From the above it will be evident that air or mixture will be drawn into the precompression chamber 27 on the up strokes of the pistons when the aprons 17, 17¹, of the pistons have uncovered the ports 26 and 26¹.

20 The air or mixture thus drawn into the precompression chamber will be compressed therein by the succeeding downward movement of the pistons, after the lower edges of the aprons 17, 17¹, of the pistons have 25 passed over and closed the ports 26 and 26¹. Opening 28 will connect with the outside atmosphere when the engine is to be provided with fuel injectors and will be connected to suitable carbureting means when the engine 30 is to be provided with spark plugs and is to operate on the usual atomized mixture of air and fuel. It has not been deemed necessary to illustrate any connection from opening 28 to a carburetor or the like, since as stated 35 the invention is applicable to both forms of engine.

The operation of the engine may be briefly described as follows. On the up stroke of the pistons air or mixture, as stated, will 40 be drawn into the precompression chamber when ports 26 and 26¹ are uncovered towards the upper limit of the pistons. When the pistons again descend this air or mixture will be compressed within chamber 27 until 45 piston 9 has nearly reached its lowest position on the down stroke, when ports 14 will be opened by the upper edge of piston 9, whereupon the compressed air or mixture in chamber 27 will pass through these ports 50 into the combustion chamber above the pistons.

Towards the end of the down stroke of the pistons, that is the working or power stroke of the pistons, the exhaust ports 13 will be opened, shortly before the inlet ports 55 14 are opened, because of the fact that piston 8 has a lead over piston 9. There will accordingly be a scavenging action of the cylinder while both exhaust and inlet ports 60 are opened, and until the exhaust ports 13 are again closed on the next up stroke of the pistons. The lead of piston 8 on the down stroke is established because of the 65 relative positions of the pistons and connecting rods with respect to the crank as

previously described, it being understood that the crank is rotating in a right-handed direction, referring to Fig. 1.

The piston 8 also establishes a lead on the up stroke, so that exhaust ports 13 will be 70 closed before the inlet ports 14 are closed. A period of supercharging then follows, the precompressed air or mixture in chamber 27 continuing to pass into the combustion chamber of the cylinder for a period while 75 the exhaust ports are closed. The inlet ports 14 are then closed and a period of compression of the air or mixture above both pistons follows. When the pistons are close to their uppermost positions the explosion or 80 combustion of a combustible mixture takes place in the combustion chamber and both pistons again start downwardly on their working stroke.

The operation of the engine is best shown 85 by the diagrams illustrated in Fig. 5, representing the relative positions of the two pistons and the opening and closing of the various ports during one complete revolution 90 of the crank. At the left of the figure the dotted circle 29 represents the travel of the 95 crank in a right-handed direction from its upper dead center position indicated at 1A, through 12A back to 1A, thirteen positions being thus indicated. The positions of the connecting rods 10 and 11 at the upper dead center position are indicated by the dot and dash lines 30 and 31, and the bottom dead center positions of the connecting rods are indicated by the lines indicated in dash at 100 30¹ and 31¹. The positions of the connecting rods for the crank position 4A are indicated by the full lines 30² and 31², which indicate the lead which piston 8 has established over piston 9 at that position, due 105 to the relative angularity of the connecting rods.

The relative positions of the pistons are illustrated graphically by the line 32, shown in dash, representing the travel of the piston 110 8 which controls the exhaust ports, and the full line 33 representing the travel of the piston 9 which controls the inlet ports. The lines 32 and 33 start together from the position 1A, as the two pistons start downwardly 115 together on their working stroke. The line 32 passes through the various positions indicated by 2A¹ etc., through 12A¹, finishing with the position 1A at the end of one revolution of the crank, while line 33, representing the travel of piston 9, passes through the positions indicated at 2A, etc., up to 12A, 120 finishing at 1A at the top of the stroke circle. Such a diagram is well known and its method of derivation need not be described. 125

Expansion of the gases doing useful work on the pistons, the exhaust ports being closed, takes place for, say, the first 120° of the stroke cycle or from position 1A to positions 5A and position 5A¹. At the posi- 130

- tion 5A¹ the piston 8 starts the exhaust stroke by opening the exhaust ports 13. At a position intermediate positions 5A and 6A, which position I have indicated as 5¹, the piston 9 opens the inlet ports 14. The scavenging stroke accordingly begins at this position 5¹, the mixture or fresh air admitted through ports 14 sweeping through the cylinder and driving the burned gases out through the exhaust ports 13 in the opposite portion 3 of the duplex cylinder. The scavenging stroke lasts until the position 8¹ is reached, intermediate positions 8A and 9A, the exhaust ports closing at position 8¹. The scavenging stroke thus continues through a crank movement extending from position 5¹ to position 8¹ during which time both the inlet and exhaust ports remain open.
- At position 8¹ the exhaust ports 13 are closed by piston 8 but the inlet ports 14 do not close until position 9A, so that the interior of the working cylinder will be supercharged with mixture or fresh air admitted from the precompression chamber 27 into the combustion chamber; that is to say, during the period from position 8¹ when the exhaust closes until position 9A is reached the engine will have a so-called supercharge stroke. From the position 9A to the position 1A the compression of the mixture or fresh air in the combustion chamber of the working cylinder will be carried out.

The pistons 8 and 9 are arranged to open ports 26 and 26¹ to admit air into the precompression chamber 27, as stated, when the pistons are approaching their upper dead center position. These ports 26, 26¹, will accordingly be closed shortly after the pistons leave their upper dead center position on their down strokes, the air or mixture being compressed in chamber 27, beneath and adjacent to the outer portions of both pistons, during the down strokes of the pistons, the inlet ports 14 beginning to open when the position 5¹ is reached from which point, as stated above, the compressed mixture or air will flow from the precompression chamber into the combustion chamber above the pistons, until the inlet ports again close at position 9A.

It will be noted from the above description that the arrangement provides for an efficient scavenging and also for a considerable supercharge of the engine. It will also be noted that the staggered relation of the cylinder portions 3 and 4, with respect to the center line of the crank shaft, permits the vertical axes of the cylinder portions 3 and 4 to be brought fairly close to the center line of the crank shaft as indicated in Fig. 2. The result of this construction is that neither connecting rod need assume a position of considerable angularity with respect to the axis of its cylinder so that the

cylinder walls are not subject to the considerable lateral pressure which would be exerted on them, or on one of the cylinder portions 3 or 4, if the cylinder portions 3 or 4 were mounted directly opposite each other on opposite sides of the center line of the crank shaft.

It will also be noted that the arrangement provides for precompression of the air or mixture within the cylinder structure itself, the precompression chamber thus formed being much smaller than the space for precompression which would be afforded if the air or mixture were precompressed in the crank case, as has previously been done. Accordingly a higher degree of precompression may readily be secured while at the same time the necessity of making the crank case air tight is obviated.

It will also be observed that the arrangement of differential pistons provided in the form of invention illustrated affords an effective means for controlling the inlet ports, exhaust ports and intake ports leading to the precompression chamber, one of the differential pistons controlling the exhaust ports while the other controls the inlet ports leading to the combustion chamber, and both of the differential pistons controlling the inlet ports leading to the precompression chamber.

It should be understood that the invention is not limited strictly to the details of construction which have been particularly described but that various equivalents of the constructions described are included within the invention, the scope of the latter being indicated by the accompanying claims.

What I claim is:—

1. In an internal combustion engine, the combination of a crank shaft, a duplex cylinder having a common combustion chamber and parallel portions arranged symmetrically with respect to the center line of the crankshaft with their center lines on opposite sides thereof, pistons in said parallel cylinder portions and connecting rods of equal length connecting said pistons with portions of the same crank of said crankshaft separated in the lengthwise direction of said crankshaft, one of said parallel cylinder portions having an exhaust opening controlled by one of said pistons and the other having an inlet opening controlled by the other piston, said parts being arranged to cause the exhaust opening to be opened and closed respectively by one piston before the inlet opening is opened and closed respectively by the other piston.

2. In an internal combustion engine, the combination of a pair of cylinder elements connected together to provide a common combustion chamber, one of the same having an exhaust opening and the other an inlet opening, pistons in said cylinder elements, a

- crankshaft, and connections between said crankshaft and pistons arranged to cause the exhaust port to be opened or closed respectively by one piston before the inlet port is opened or closed by the other piston, said cylinder elements being staggered in the axial direction of the crankshaft and arranged symmetrically with respect to the center line of the crankshaft.
3. In an internal combustion engine, the combination of a crankshaft, a duplex cylinder having parallel portions extending at right angles to the axis of said crankshaft, with their center lines on opposite sides of the center line thereof, at equal distances therefrom, and said portions being staggered in the axial direction of the crankshaft, pistons in said parallel portions, and connections between said pistons and the same throw of said crankshaft.
4. In an internal combustion engine, the combination of a duplex cylinder having two working portions, one having an exhaust port and the other an inlet port, the cylinder being arranged to provide a pre-compression chamber, having inlet ports, in both portions, and pistons in said working cylinder portions, one of which controls the exhaust and the other the cylinder inlet port, while both of them control the opening and closing of the precompression chamber inlet ports.
5. In an internal combustion engine, the combination of a duplex cylinder having two working portions, one having an exhaust port and the other an inlet port, and differential pistons in said working cylinder portions, precompression spaces, connected together, being provided in both cylinder portions beneath said pistons, the said cylinder inlet port opening into said space and being controlled by one of said pistons, and both working portions of said cylinder having intake openings leading into said space, controlled by both of said pistons.
6. In an internal combustion engine, the combination of a crank shaft, a duplex cylinder having parallel portions arranged with their center lines on opposite sides of the center line of the crank shaft, at equal distances therefrom and said portions being staggered and overlapping each other in the axial direction of the crank shaft, pistons in said parallel portions and connections between said pistons and crank shaft.
7. In an internal combustion engine, the combination of an engine structure having a pair of cylinder elements connected together to provide a common combustion chamber at one end and a precompression chamber at the other end, one of said cylinder elements having an exhaust port and the other having an inlet port extending into the same from said precompression chamber, said precompression chamber having an inlet port, pistons in said cylinder elements arranged to open and close said cylinder inlet and exhaust ports and to precompress gaseous mixture in said precompression chamber, a crankshaft and connections arranged to cause one piston to obtain a lead over the other, each stroke, to cause the exhaust port to be opened and closed, respectively, by said piston, before the cylinder inlet port is opened and closed, respectively, by the other piston, one of said pistons controlling the pre-compression chamber inlet port.
8. In an internal combustion engine, the combination of a crankshaft, a pair of cylinder elements connected together to provide a common combustion chamber, precompression spaces being provided in both cylinder elements, connected together, said precompression spaces having inlet ports, one of said cylinder elements having an exhaust port and the other having an inlet port connecting with one of said precompression spaces, pistons in said cylinder elements arranged to open and close said cylinder inlet and exhaust ports, respectively, and both pistons being arranged to open and close said precompression space inlet ports, a crankshaft and connections between said crankshaft and pistons arranged to cause the exhaust port to be opened and closed, respectively, by one piston, before the cylinder inlet port is opened and closed, respectively, by the other piston.

In testimony whereof I have signed my name to this specification at New York, N. Y., this 15th day of March, 1922.

CHARLES J. TÓTH.
